UNITED STATES PATENT OFFICE.

CHARLES W. HAWTHORNE, OF SHREWSBURY, MASSACHUSETTS, ASSIGNOR, BY MESNE ASSIGNMENTS, TO THE CHASE NATIONAL BANK OF THE CITY OF NEW YORK, TRUSTEE, OF NEW YORK, N. Y.

TOOL FOR BENDING METAL FABRICS.

Application filed October 20, 1923. Serial No. 669,836.

This invention relates to a tool for bending metal fabric and particularly for bending the fabric used in concrete and cement structures of different kinds. The fabric used for such purposes may be woven, welded or formed of perforated metal, but in any event it is stiff and heavy and very difficult to bend to a desired form. Furthermore, it is commonly necessary that the fabric be bent at the location where it is to be used and where suitable mechanical equipment is usually lacking.

It is the object of my invention to provide a simple and convenient tool by which such fabric may be bent to a desired form, producing accurate results with a marked saving in time and labor.

In the preferred form of my invention, I provide a device for engaging and pressing downward a portion of the fabric, a separate device for engaging and raising or bending upward another portion of the fabric and means to secure said devices in selected spaced relation.

My invention further relates to arrangements and combinations of parts which will be hereinafter described and more particularly pointed out in the appended claims.

A preferred form of the invention is shown in the drawings, in which

Figure 1 is a perspective view of my improved bending tool;

Fig. 2 is a detail plan view looking in the direction of the arrow 2 in Fig. 1; and

Figs. 3 to 6 inclusive are diagrammatic views illustrating certain uses of the bending tool.

Referring to the drawings, my improved bending tool comprises a cross bar 10 from the rear ends of which project a pair of rods 11 having handle portions 12 projecting upwardly at an oblique angle therefrom. A lifting bar 13 is slidably mounted on the rods 11 and is provided with a plurality of V-shaped notches 14 terminating in offset recesses 15 disposed above hook-like projections 16.

The lifting bar 13 may be adjusted on the rods 11 to vary the distance between the cross bar 10 and the lifting bar 13, the bar being secured in adjusted position by set screws 17 (Fig. 2) engaging the supporting bars 11.

The cross bar 10 may be formed from a

piece of angle iron with its flat side in position to engage the fabric as indicated in Figs. 3 to 6. The lifting bar 13 may also desirably be formed of a single flat bar or plate bent at the ends as indicated in Fig. 2 and cut away to form the recesses and hook-like projections previously described.

It will be understood that the notches or recesses 14 are spaced to correspond to the gauge or distance between the wires in the fabric with which the tool is to be used and that a cross bar of different gauge or spacing should be provided for each different gauge of fabric, except that the same spacing may be used for different gauges which are multiples of each other. That is, a one-inch gauge may be also used for fabric in which the wires are spaced two inches or three inches apart while a three-quarter inch gauge may be similarly used for one inch and a half, two and a quarter, or three inch gauge.

The operation of my improved bending tool is clearly set forth in Figs. 3 to 6 inclusive, which illustrate one of the uses to which my improved tool is well adapted.

These figures illustrate the bending of material for reinforcing concrete floors or floor slabs. A mesh fabric F is conveniently supported upon blocks B and B' and may be held in position on one of the blocks by placing a plank C over the fabric, on which plank the operator may stand.

The bending tool is applied to the fabric as indicated in Fig. 3, with the hook-like projection 16 extending through the meshes of the fabric and engaging the longitudinal wires thereof.

The tool is then moved to the position shown in Fig. 4, swinging substantially about the cross bar 13 as a pivot and bending the wire downward as indicated. The tool is then removed and transferred to the opposite edge of the fabric and the fabric is again placed upon the blocks B and B' and is clamped to the block B' by the plank C as indicated in Fig. 5. The bending tool is then used to form a similar but oppositely disposed bend along the second edge of the fabric and produces the desired finished outline indicated in Fig. 6.

Many other uses of the bending tool will suggest themselves to those skilled in the art and while particularly adapted for bending fabric it will be evident that the device

is also available for bending either one or a plurality of longitudinal rods, even when not interwoven or otherwise secured to form a fabric.

5 Having thus described my invention and the advantages thereof I do not wish to be limited to the details herein disclosed otherwise than as set forth in the claims, but what I claim is:—

- 10 1. A tool for bending metal fabric comprising a fabric engaging cross bar, operating means fixed thereto, and a fabric lifting bar mounted on said operating means, said lifting bar having a plurality of spaced hook-shaped projections to engage and lift portions of the fabric, and said projections having V-shaped lower ends facilitating application of said bending tool to the metal fabric.
- 15

2. A tool for bending metal fabric comprising a fabric engaging cross bar, a pair of metal rods fixed thereto, a fabric lifting bar slideable on said rods and having spaced fabric engaging portions, and means to adjust said lifting bar on said rods toward 25 and from said cross bar.

3. A tool for bending metal fabric comprising a fabric engaging angle iron cross bar, a pair of rods fixed thereto and having handle portions bent obliquely upwardly therefrom, a fabric lifting bar slideable on said rods and having spaced fabric engaging projections, and means to adjustably secure said lifting bar on said rods at a selected distance from said cross bar.

35 In testimony whereof I have hereunto affixed my signature.

CHARLES W. HAWTHORNE.
